(57) **CLAIM**

We claim the ornamental design for the rod support arm, as shown and described.

DESCRIPTION

FIG. 1 is a top perspective view of a rod support arm in accordance with of our new design;

FIG. 2 is a front elevation view of the rod support arm of FIG. 1;

FIG. 3 is a rear elevation view of the rod support arm of FIG. 1;

FIG. 4 is a left-side elevation view of the rod support arm of FIG. 1, the right-side elevation view being a mirror image thereof;

FIG. 5 is a top plan view of the rod support arm of FIG. 1; FIG. 6 is a bottom plan view of the rod support arm of FIG. 1; and,

FIG. 7 is a bottom perspective view of the rod support arm of FIG. 1.

The broken lines in the drawings illustrate portions of a rod support arm which form no part of the claimed design.
